UNITED STATES PATENT OFFICE

2,468,899

ALKYLATION OF HYDROCARBONS

Carlisle M. Thacker, Highland Park, Ill., assignor
to The Pure Oil Company, Chicago, Ill., a cor-
poration of Ohio

No Drawing. Application March 15, 1945,
Serial No. 582,990

8 Claims. (Cl. 260—683.4)

1

This invention relates to the reaction of paraffins with olefins at elevated temperatures and pressures to form higher-boiling saturated hydrocarbons.

Reaction of normal- and iso-paraffins having from 3 to 5 carbon atoms in the molecule with unsaturated hydrocarbons such as ethylene, propylene, butylene, acetylene and butadiene at temperatures within the range of approximately 750-1200° F. and at pressures of from 500-5000 pounds per square inch or more have been suggested in the prior art. In one type of process, the paraffins are passed through an elongated reaction coil wherein they are heated to the desired reaction temperature under the desired pressure, and olefins are injected into the coil at a plurality of spaced points in order to maintain the olefin concentration in the mixture between approximately 2 to 10 per cent by weight. Processes of this type are disclosed in United States Patents 2,002,394, 2,104,296 and 2,270,700. In another type of process for reacting paraffins with olefins, a mixture containing in excess of 50 per cent of paraffins and in excess of 10 per cent of olefins is heated to the desired reaction temperature under reaction pressure and charged to an enlarged reaction zone of such structure as to cause a high degree of circulation and turbulent mixing therein. Such a process is disclosed in United States Patent 2,266,019.

I have discovered that reaction between paraffins and olefins under high temperature-high pressure conditions can be greatly accelerated if the reaction is carried out in the presence of a promoter comprising a small amount of a mixture of bromine with one or more compounds selected from the group consisting of carbon tetrachloride, carbon tetrabromide, chloroform and bromoform.

An object of the invention is to provide an improved process for reacting paraffins with olefinic hydrocarbons.

Another object of the invention is to provide a promoter for accelerating the rate of reaction of paraffins with olefinic hydrocarbons under elevated temperature and pressure.

Still another object of the invention is to provide a process in which increased yields of saturated hydrocarbons of high octane value can be obtained from the reaction of olefins and paraffins at elevated temperature and pressure.

A still further object of the invention is to provide a process in which a more valuable product can be obtained by reaction of olefins and paraffins at elevated temperature and pressure.

2

In accordance with my invention, paraffinic hydrocarbons which may consist of normal paraffins or isoparaffins having from 3 to 7 carbon atoms per molecule, such as propane, butane, isobutane, pentane, hexane and heptane, or any mixture thereof, may be heated to a temperature of approximately 750-1100° F. in a heating coil, after which gas or liquid rich in olefins, as for example ethylene, propylene, butylenes, amylenes, or stabilizer gas separated from low pressure, high temperature thermally cracked gasoline, is injected into the heated stream of paraffinic hydrocarbons at a plurality of points in the manner disclosed in the aforesaid patents in order to keep the olefin concentration between approximately 2 to 10 per cent by weight of the mixture. A mixture of carbon tetrachloride, carbon tetrabromide, chloroform or bromoform, or any combination thereof, with bromine, is added to the charge undergoing reaction in an amount ranging from approximately 0.5 to 10 per cent by weight of the total hydrocarbon charge. The amount of bromine is preferably between 0.1 per cent by weight and 5 per cent by weight of the hydrocarbon charge, and the carbon tetrachloride, or other group compound, is preferably between 0.4 and 9.9 per cent by weight of the hydrocarbon charge. The entire amount of promoter may be mixed with the liquid paraffins charged to the heating coil, or the promoter may be injected into the reaction coil at a plurality of points.

Admixture of bromine with olefins charged to the system before mixture of the olefins with the paraffins should be avoided because of the fact that bromine readily reacts with unsaturates.

When the process is carried out using a turbulent reactor such as disclosed in Patent 2,266,019 the hydrocarbons charged to the process may be the gases from a high pressure thermal or a catalytic cracking process from which the major portion of the methane and hydrogen have been removed. Ordinarily, these gases will contain considerably less than 50 per cent of olefins with the major portion consisting of C₃ and C₄ paraffins. In this type of operation the promoter is preferably injected directly into the reaction zone in order to prevent bromination of the olefins before the reactants are heated to reaction temperature. However, the effect of the promoter can be realized to a large extent even where the catalyst is mixed with the charging gas prior to charging it to the heating coil.

In carrying out the reaction temperatures of 55 750-1100° F. and pressures in excess of 500

pounds, and preferably in excess of 2,000 pounds per square inch are maintained in the reaction zone. Conversion rates equalling those obtained in purely thermal operations can be obtained using promoters in accordance with my invention at considerably lower temperatures. Under the same conditions of temperature and pressure when promoters in accordance with my invention are used, the rate of conversion is greatly accelerated with the result that a higher yield of desirable high octane hydrocarbons boiling within the gasoline range is obtained. Isoparaffinic charging stocks require lower temperatures and pressures than are required for normal paraffinic charging stock to obtain the desired amount of alkylation. The time of reaction should be sufficient to cause the major portion of the olefins to be converted to higher boiling hydrocarbons but insufficient to cause substantial cracking of the paraffinic charging stock to lower boiling hydrocarbons. Reaction times may vary from a few seconds to approximately 10 minutes depending on the temperature, pressure and reactants. Higher pressures and temperatures accelerate the reaction for any given charging stock.

As an example of the process a feed stock comprising chiefly straight and branched chain hydrocarbons having 3 to 7 carbon atoms per molecule is mixed with a mixture of ethylene and propylene so that the resultant mixture contains less than 10 per cent by weight of olefins. To this mixture is added 3 per cent by weight of carbon tetrachloride and 0.5 per cent by weight of bromine. The mixture is passed through a reaction coil wherein it is heated to 940° F. under a pressure of 2,000 pounds per square inch, and is permitted to remain in the reaction coil for a sufficient period of time to permit substantially all the propylene to react with the paraffins and more than 60 per cent of the ethylene to react. The resulting liquid product will be a gasoline of high octane number and high blending value suitable for aviation gasoline after it has been freed of halogens by neutralization with alkali, or other suitable method. Under these same conditions of temperature and pressure the time required to obtain the same amount of conversion is considerably longer.

It is claimed:

1. The method of reacting paraffins having at least 3 carbon atoms per molecule with olefinic hydrocarbons comprising subjecting a mixture of said paraffins and olefinic hydrocarbons to temperatures of approximately 750°-1100° F. and pressures in excess of 500 pounds per square inch

in the presence of a small amount of bromine and a small amount of carbon tetrachloride.

2. The method of reacting olefinic hydrocarbons with paraffin hydrocarbons comprising subjecting a mixture of paraffin hydrocarbons comprised chiefly of hydrocarbons having from 3 to 7 carbon atoms per molecule and not more than 10% by weight of olefins containing 3 to 5 carbon atoms per molecule to temperatures of 10 the order of 750 to 1100° F. at pressures in excess of 2,000 pounds per square inch in the presence of approximately 0.1 to 5 per cent by weight of bromine and approximately 0.4 to 9.9 per cent by weight of a compound selected from the group 15 consisting of carbon tetrachloride, carbon tetrabromide, chloroform and bromoform for a period of time sufficient to permit the major portion of the olefins to react to form higher boiling hydrocarbons.

3. Method in accordance with claim 2 in which the group compound is carbon tetrachloride.

4. The method of reacting paraffins having at least 3 carbon atoms per molecule with olefinic hydrocarbons comprising, subjecting a mixture 25 of said paraffins and olefinic compounds to temperatures of approximately 750°-1100° F. and pressures in excess of 500 pounds per square inch in the presence of a catalyst consisting of about 0.1 to 5 per cent of the charge by weight of bromine and 0.4 to 9.9 per cent of the charge by weight of a compound selected from the group 30 consisting of carbon tetrachloride, carbon tetrabromide, chloroform, and bromoform.

5. The method in accordance with claim 4 35 in which the catalyst consists of bromine and carbon tetrachloride.

6. The method in accordance with claim 4 in which the pressure is in excess of 2,000 pounds per square inch.

40 7. The method in accordance with claim 4 in which the olefinic hydrocarbon content of the mixture is below 50 per cent by weight.

8. The method in accordance with claim 4 in which the olefinic hydrocarbon content of the 45 mixture is below 10 per cent by weight.

CARLISLE M. THACKER.
